DESIGN FOR A REFRESHMENT STAND

Carl F. Krueger, Webster Groves, and Albert R. Krueger, Northwoods, Mo.

Application October 9, 1947, Serial No. 141,836

Term of patent 14 years

(Cl. D13—1)

To all whom it may concern:

Be it known that we, Carl F. Krueger and Albert R. Krueger, citizens of the United States, residing at Webster Groves and Northwoods, respectively, in the county of St. Louis and State of Missouri, have invented a new, original, and ornamental Design for a Refreshment Stand, of which the following is a specification, reference being had to the accompanying drawing, forming part thereof.

We claim:

The ornamental design for a refreshment stand, as shown.

CARL F. KRUEGER.
ALBERT R. KRUEGER.
